UNITED STATES PATENT OFFICE.

GABRIEL A. PETIT, OF CHICAGO, ILLINOIS, ASSIGNOR TO IMPERIAL PLAYER ROLL COMPANY, OF CHICAGO, ILLINOIS, A CORPORATION OF ILLINOIS.

DESIGN FOR A LABEL-BLANK.

46,182.

Specification for Design.

Patented July 28, 1914.

Application filed May 29, 1914. Serial No. 841,922. Term of patent 14 years.

To all whom it may concern:

Be it known that I, GABRIEL A. PETIT, a citizen of the United States, residing at Chicago, in the county of Cook and State of Illinois, have invented a new, original, and ornamental Design for a Label-Blank, of which the following is a specification, reference being had to the accompanying drawing, forming a part thereof.

The figure shows my new design.

I claim:

The ornamental design for a label blank, as shown.

GABRIEL A. PETIT.

Witnesses:

W. N. JOHNSON,
J. CLARKE HAGEY.
